(57) **CLAIM**

The ornamental design for a hood panel of a car, as shown and described.

DESCRIPTION

FIG. 1 is a front perspective view of the hood panel of a car showing my design thereof;

FIG. 2 is a rear perspective view thereof;

FIG. 3 is a front view thereof; and,

FIG. 4 is a top plan view thereof.

Portions of the car shown in broken lines form no part of the claimed design.

1 Claim, 4 Drawing Sheets

FIG. 1

FIG. 2

FIG. 3

FIG. 4
